UNITED STATES PATENT OFFICE.

ARTHUR E. H. BARILI, OF LOS ANGELES, CALIFORNIA, AND THEODORE F. VON DORN, OF NEW YORK, N. Y.; SAID BARILI ASSIGNOR TO SAID VON DORN.

RAIL ANCHOR FOR RAILWAYS.

Application filed June 7, 1928. Serial No. 283,534.

This invention relates to an improved and novel type of rail anchors and the method of making the same, said anchors being especially designed to be secured to the base portion of railroad track rails and in engagement with the stationary parts of the road bed for the purpose of preventing longitudinal displacement or creeping of the track rails when subjected to the excessive strains caused by 5 the travel of the heavy rolling stock over and upon the said rails.

The main object of this invention is to provide a novel, simple, durable, economical, practical and thoroughly efficient rail anchor 15 from a single piece of metal preferably of high grade spring steel possessing sufficient strength to safely withstand all of the strains to which devices of this character are usually subjected, which may be easily and readily 20 applied to the base portion of a railroad rail and securely retained in its operative position thereon, and which will effectually grip the rail and co-operate with the stationary part of the road bed to prevent the rail from 25 creeping under any and all conditions of service.

Another object of the invention is to so construct our improved device that any tendency of the rail to creep or move forwardly during the travel of the rolling stock 30 thereon, will simultaneously cause the anchor to impart a greater and more intense grip to the base portion of the rail at each side thereof, and thus effectually arrest and retard 35 such creeping or forward movement of the rail.

Further objects of the invention are to so construct our device that it may be stamped or punched from a sheet of suitable rolled steel, 40 hot or cold, at a single operation; that it may be so punched from the said sheet of steel that only the minimum amount of waste steel remains, and then by properly heating the punched out blank so bend the said blank by 45 a single machine as to produce the finished anchor device.

The foregoing and such other objects as may appear from the ensuing description are accomplished by the construction, arrangement, location and combination of the parts hereinafter more fully described, illustrated 50 in the accompanying drawings, and particularly pointed out in the claims appended hereto, it being understood that slight changes 55 in the precise form, proportions and minor

details of the construction may be resorted to without departing from the spirit or sacrificing any of the advantages of the invention.

In the accompanying drawings forming a part of this specification, it will be seen that: 60

Figure 1 is an elevation of the device embodying our invention, showing said device applied to a track rail in contact with a cross-tie, with the said rail in cross-section.

Figure 2 is an end view of the device applied to the track rail in contact with the cross-tie with the rail in side elevation and the cross-tie in cross-section. 65

Figure 3 is a plan view of the same.

Figure 4 is a bottom plan of the device removed from the track rail. 70

Figure 5 is a side elevation of a slightly modified form of our anchor device applied to a track rail, showing the rail in cross-section and a side elevation of a cross-tie. 75

Figure 6 is an end view of the same, showing the cross-tie in cross-section and the rail in side elevation.

Figure 7 is a plan of the same.

Figure 8 is a bottom plan of the modified 80 form of the device removed from the rail.

In the embodiment of our invention as illustrated it will be seen that the numeral 1 indicates a railroad track rail and 2 an underlying cross-tie forming a stationary part 85 of the road bed and supporting the rail 1 and over which the rail has a tendency to creep forwardly when subjected to the intense and excessive strains caused by the passage of the heavy rolling stock thereover. 90

Our novel rail anchor 3 is fixedly secured to the base of the track rail and it is formed of a single piece by punching or stamping a suitable blank from a flat rolled bar of high grade spring steel or other suitable metal, 95 after which the blank is properly heated, and by a single machine is bent into the finished formation, such as is shown in the drawings.

The anchor 3 thus formed and secured to the rail comprises a comparatively large 100 headed portion 5 formed with an inwardly extended jaw member 6 adapted to rigidly engage and clamp the upper face of the rail base 7 inwardly from the edge thereof, said member 6 being formed with a vertical downwardly extended body portion 8, the inner face of said portion 8 being adapted to contact with the cross-tie throughout the depth of said face. 105

It will be perceived that in the upper face 110

of the head portion is formed a curved depression or recess 9 so that when the anchor is being applied in its proper operative position to the track rail, the sharp or square corner 5 of one edge of the rail base will readily slide through the recessed portion and the edge of the rail will rest in contact with the edge 10 of the jaw with the portion 11 of the anchor resting in contact with the lower face of the 10 rail base, said recess serving to release considerable strains from the curved arm 10', and at the left of said recess 9 is a portion 12 of the anchor, which contacts with the lower face of the rail base in horizontal alinement 15 with the portion 11, while the outwardly bent or curved arm or member 10' is so formed as to not contact with the lower face of the rail, and terminates at its outer end with an upright clamping portion 13 adapted to engage and tightly clamp the other edge of the rail, as clearly shown in Fig. 1. The terminal or outer end portion 13 of the curved arm or resilient member 10' is bent inward slightly, as shown in Fig. 4, and before being forced 20 or sprung outwardly to clamp the edge of the rail it rests in contact with the lower face of the rail base, but immediately upon being forced outwardly by a suitable tool until it passes the lower face of the rail base it will 25 snap upwardly against and tightly clamp the edge of the said rail base.

It will be observed that the smooth inner face of the body portion of the anchor at the point 14 rests in contact with the tie throughout 30 its downwardly extended portion thereby preventing any cutting, lacerating or damaging of the tie.

It will be seen that the anchor is formed with rounded corners at the points 16 and 16', 40 thereby materially lessening any tendency of the anchor to break off at said points when subjected to heavy and excessive strains.

In applying the anchor to the rail, the anchor is first placed in its proper position 45 relative to the rail with the inner end of the jaw member 6 in engagement with the upper inclined face of the rail base with its depending body portion 8, and bent hook-shaped member 10' and its terminal portion 13 resting beneath the bottom of the rail, with said portion 13 in contact with the lower face of the rail base and in comparatively close proximity to the edge of said base, thus causing the said member 10' to be under a resilient upward tension, so that when a suitable tool, 50 which is provided, is employed, to engage the outer inwardly bent terminal portion of the resilient member 10' and sufficient pressure is applied thereto the said terminal portion 55 will slide along the rail base until it passes the edge of said base, when it will immediately spring upwardly and tightly clamp the edge of the rail base with the central portion of the member 10' resting slightly away 60 from contact with the rail base, in the man-

ner shown in Fig. 1, and the tendency of the resilient terminal end portion of the anchor to return to its original shape results in an extreme and intense gripping action on the rail base, such gripping action being more 70 than sufficient to retain the anchor in its proper secured position regardless of any and all vibrations to which the rail may be subjected, and in spite of weather changes or the like.

Referring now to the slightly modified form of anchor, such as is shown in Figs. 5, 6, 7 and 8, respectively, it will be seen that the anchor is formed of somewhat thinner material than the body portion 16 being doubled or folded upon itself throughout its length and breadth with the folded portions 18 resting in spaced relation to each other to form what may be properly termed a cushion-like structure, hence when the traffic is all in one direction it forces the rails forward until all anchors are resting solidly against the cross-tie, and when a train passes on the track and forces a wave-like motion to the rails, also a sudden application of the brakes imparts an unusual forward force to the rails and since the anchors are already in solid contact with the ties there can be no give or yield with the result that the ties must be forced forward with the ballast which displaces the tie to some extent and throws all resistance on the rail joint that is secured to one or both of the ties, while our double bent rail anchor being folded in spaced relation with the two laps of steel disposed slightly apart, when thus forced against the tie by sudden and excessive pressure the anchor strikes the tie with a cushioning effect to receive the force and when the train has passed the resilient pressure of the anchor returns the folded portion to its normal position 95 ready to receive the next force produced by a train passing over the track rail, and while the spring action is not extensive it is sufficient to counteract the sudden force of the rail and create a cushioning effect. The folded over portion produces a double jaw formation, 100 which constitutes an exceedingly strong reinforced jaw member, while the curved resilient hook-shaped member 19 and its terminal portion 20 are formed and function substantially 105 the same as the anchor hereinbefore first described.

It will be understood that our improved anchor may be formed of any thickness or any suitable or desirable dimension which may be desired or required for the purposes for which it is to be utilized.

Having thus described our invention what we claim and desire to secure by Letters Patent is:

1. A rail anchor comprising a jaw member, an integral downwardly extended body portion terminating at its lower end in vertical alinement with the outer edge of the jaw member and parallel with the upper edge of said 130

- jaw member and formed with an inner smooth face adapted to contact with a cross-tie, an upward extension formed at the other end, and an intermediate outwardly extended hook-shaped portion.
2. A rail anchor comprising a jaw member, a downwardly extended body portion terminating at its lower end in vertical alinement with the outer edge of said jaw member and parallel with the upper edge of said jaw member and formed with a smooth inner face adapted to contact with a broadened cross-tie throughout its depth, an upward clamping extension formed at its other end, and an intermediate laterally extended hook-shaped portion.
3. A rail anchor formed from a single piece of metal, comprising a jaw member and a downwardly extended body portion terminating at its lower end in vertical alinement with the outer edge of the jaw member, and an intermediate outwardly extended resilient portion bent inwardly at its outer end and formed with an upright terminal clamping extension.
4. A single piece rail anchor for track rails of the character described, comprising a jaw member and a body member formed at one end thereof in vertical alinement throughout, a semi-circular depression formed in its upper
- face intermediate its ends, an upwardly extended portion at each side of said depression adapted to contact with the lower face of the rail, and an intermediate outwardly extended resilient curved portion away from contact with the rail, said curved portion being bent inwardly at its outer end and provided with an upright rail clamping extension.
5. A single piece rail anchor for track rails, comprising a jaw member and a body portion formed at one end thereof disposed in vertical alinement with the outer edge of said jaw member, a recess formed in its upper edge intermediate its length, an upward extension formed at each side of said recess adapted to contact with the lower face of the rail, a laterally extended resilient intermediate hook-shaped portion, and an upwardly extended clamping portion at its other end.
6. A single piece rail anchor for track rails, comprising a jaw member and body portion folded upon itself in spaced relation to form a cushion effect at one end thereof, a laterally and rearwardly extended resilient intermediate hook-shaped portion, and an upward clamping extension formed at its other end.

ARTHUR E. H. BARILLI.
THEODORE F. von DORN.
